UNITED STATES PATENT OFFICE.

WILLIAM E. HANCOCK, OF TULSA, OKLAHOMA.

GAS BURNER.

Application filed March 18, 1922. Serial No. 544,936.

To all whom it may concern:

Be it known that I, WILLIAM E. HANCOCK, a citizen of the United States of America, and resident of Tulsa, in the county of Tulsa, and State of Oklahoma, have invented certain new and useful Improvements in Gas Burners, of which the following is a specification.

This invention relates to gas burners, and has for an object the provision of novel means for feeding gas and steam to a furnace, the steam acting to enrich the gas and produce qualities which will result in increasing effective combustion of the fuel mixture as it issues from jets or nozzles stationated within the fire box of a furnace.

A further object of this invention is to provide novel means for controlling the mixture of gas and steam, and other means actuated by the pressure of the steam for operating the controls of the steam and gas.

It is a further object of this invention to produce a self-regulating fuel mixing and delivering apparatus in which the pressure of steam within the boiler of a furnace during its rise and fall will automatically diminish or increase the supply of gas and steam to the burners of the furnace.

A still further object of this invention is to provide means for regulating the controls or valve of the steam and gas delivery pipes, in order that the mixture may be changed to make it richer or leaner, according to the requirements in practice and the condition of gas being consumed.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a perspective view of the fuel mixing and delivering mechanism associated with a furnace;

Figure 2 illustrates a sectional view of a mixing head showing its internal mechanism in plan;

Figure 3 illustrates an enlarged detailed

sectional view of one of the nozzles or jets for delivering fuel;

Figure 4 illustrates a view in elevation of a portion thereof;

Figure 5 illustrates a sectional view on the line 5—5 of Fig. 4;

Figure 6 illustrates a sectional view of the control for the nozzle; and

Figure 7 illustrates a view in elevation of the end fitting for the nozzle.

In these drawings 1 denotes the head of a nozzle or jet, the said head having air vents 2 therein to effect the circulation of air through the nozzle. It will be understood that one or more nozzles can be employed in connection with this invention and hence the number is immaterial. A tube 3 extends through the head and the tubular portion thereof is intersected by a plug 4 with ports 5 and 6 extending through it, one preferably at right angles to the other, and one of which is of greater capacity than the other, in order that the amount of fuel passing through the tube may be regulated.

The tube has a threaded nipple 7 which enters an aperture 8 in a pipe 9 that extends preferably longitudinally of the fire box, and in this illustration of the invention, two tubes 9 are shown located in the fire box with the nozzles extending therefrom at angles, and preferably the angular position of the nozzles with relation to the pipes to which they are attached is 45 degrees, although, of course, this may be changed to suit particular requirements.

The nozzle includes a shell-like structure or tube 10 applied to the head, and the outer end of this tube has an angularly disposed lip or flange 11 constituting a baffle or deflector which is encountered by the fuel so that the fuel is deflected from the course on which it enters the nozzle. The manner of assembling the head and the parts associated with it may be changed to suit particular requirements, as one skilled in the art will understand.

The means for supplying a mixture of gas and steam to the burners or jets includes a header or mixing chamber 12 through which, in the present embodiment of the invention, a steam pipe 13 extends, and it is secured therein by resting in apertures of the end walls of the header. The steam pipe

is closed at one end by a plug 14 and the said steam pipe has a branch 15 extending outwardly through the wall of the header and it is connected to a branch 16 of a steam pipe 17.

The header has hollow branches or extensions 18 to which the pipes 9 are connected for delivering fuel to the furnace. The steam pipe 13 has jets 19 connected to it, 10 and these jets extend through the hollow branches of the header and preferably extend slightly into the pipes 9 in order that when steam is supplied to the pipe 13, it will act on and be commingled with gas 15 which is delivered through the header, as will presently appear.

The pipe 17 leads to the source of steam supply such as the furnace boiler, and it supplies steam to the pipe 16 and to an extension 20 thereof, which extension constitutes a support for a pressure actuated mechanism 21 for controlling the valves of the steam and gas supply pipes, as will presently appear. The pressure actuated mechanism 25 may be in the nature of a diaphragm or like device to be moved by the pressure of steam, and as these devices are well known in the art, it is believed that a detail illustration or description thereof will 30 be unnecessary.

A post 22 may, of course, extend from within the pressure actuated mechanism, and a lever 23 may be pivoted on the post and hinged as at 24, to a bracket 25, supported in any appropriate way. The bracket has a bifurcated arm 26 constituting a guide for the lever 23, and the said lever is supplied with an adjustable weight 27, the movement of which weight on the lever 40 will control the movement of the lever or require different pressures from within the pressure actuated mechanism to effect a movement of the lever. The bracket may be supported by a post 28 having its lower 45 end anchored to one of the branches 18 of the header, although other means may be employed for holding the bracket in operative relation to the other parts of the mechanism.

50 The steam delivery pipe 29 is coupled to the pipe 13, and a valve 30 of suitable construction may be interposed in the pipe to control the delivery of steam to the header. The valve stem 31 has an arm 32 secured 55 on it, by which the stem is partially rotated when the arm is oscillated, and the said arm has apertures 33 to receive a pivot 34 of a link 35, so that when motion is communicated to the link, the said arm will be raised 60 or lowered at its outer end, and the interior mechanism of the valve is such that this movement will open or close the ports of the valve to increase or diminish the supply of steam to the header.

65 The gas delivering pipe 36 is coupled to

the header through a nipple 37, and the gas pipe is provided with a valve 38 similar to the valve 30. The valve 38 is controlled by the oscillated arm 39 which is secured to the valve stem 40, and the said arm 39 has motion imparted to it through the medium of a link 41 which is pivotally connected to the lever 23 and to the said arm. Provision is made for adjusting the point of connecting the link 41 to the arm to increase or diminish the throw or movement imparted to the arm by the lever 23.

70 It will be seen from an inspection of the drawing that the valves 30 and 38 are controlled simultaneously and that they are actuated by the pressure within the boiler. As steam rises, the lever 23 is pressed upwardly, whereas upon the pressure diminishing, the weight 27 will force the outer end of the lever downwardly and actuate the valves in a direction opposite to that in which they were actuated by the lifting of the lever 23, due to the pressure within the boiler.

75 The steam pipes 13 has branches 42 and 43 opposite the steam jets 16, and these branches are closed by plugs 44, the removal of which will permit access to the interior of the steam nipples in order that deposits 80 may be removed therefrom.

85 The head has lugs 45 which engage the tubular member and serve to hold it in place.

90 The mechanism just described will prove effective to maintain pressures in boilers substantially uniform when the valves in the gas and steam supply pipes have been properly set for the needs of the particular boiler or furnace, for the valves and the valve operating mechanism will be set to supply a maximum amount of fuel for a given furnace until the steam has reached a predetermined pressure, at which time, the steam actuated device for operating the valves will operate the valves to cause a diminishing flow of gas and steam. Should the pressure of steam fall below a predetermined point, the weight will overcome the pressure of steam and cause an opening 95 or partial reopening of the valves in order that the fuel delivered to the burners will be increased. By having the parts of the apparatus operate under what might be termed "sensitive" conditions, the pressure in the boiler could be maintained practically uniform and of course automatically, since the actuation of the valves is practically automatically accomplished.

100 I claim:

1. In a furnace fuel feeding apparatus, a 105 header having branches, fuel feeding pipes connected thereto, burners radiating from the said pipes and extending obliquely with relation to the axis of the pipes, means for supplying gas to the header, a steam pipe 110

- extending into the header and having jets discharging through the branches of the header and mixing the steam and gas, a steam actuated element in communication with the steam supplying pipe, a member moved by said element, valves for controlling the steam and gas supply pipes, and means for communicating the motion of the member to the said valves.
- 5 2. In a furnace fuel feeding apparatus, a header having branches, fuel feeding pipes connected thereto, burners radiating from the said pipes and extending obliquely with relation to the axis of the pipes, said burners each comprising a tube carried by a pipe, means for regulating the flow of fuel through the said tube, a head having vents therein applied to the tube, a hollow body forming an extension of the head and having a flanged extension forming a baffle partly guarding the outer end of the body, means for supplying gas to the header, a steam pipe extending into the header and having jets discharging through the branches of the header and mixing the steam and gas, a steam actuated element in communication with the steam supplying pipe, a member moved by said element, valves for controlling the steam and gas supply pipes, and means for communicating the motion of the member to the said valves.
- 10 3. In a furnace fuel feeding apparatus, a header having branches, fuel feeding pipes connected thereto, burners radiating from the said pipes and extending obliquely with relation to the axis of the pipes, said burners each comprising a tubular member connected to the fuel pipe, a head having vents therein applied to the tube, lugs on the said head projecting beyond the side of the head, a body fitted to the head and resting on the lugs, said tube having a portion of its wall extended and shaped to partially guard the opening in the body for deflecting the fuel, means for supplying gas to the header, a steam pipe extending into the header and having jets discharging through the branches of the header and mixing the steam and gas, a steam actuated element in communication with the steam supplying pipe, a member moved by said element, valves for controlling the steam and gas supply pipes, and means for communicating the motion of the member to the said valves.
- 15 4. In a furnace fuel feeding apparatus, a header having branches, fuel feeding pipes connected thereto, burners radiating from the said pipes diagonally with relation to the axes thereof, said burners each comprising a tube carried by a pipe and having means for regulating the flow of fuel through said tube and a head having vents therein applied to the tube, a hollow body forming an extension of the head and having a flanged extension forming a baffle partly guarding the outer end of the body, and means for supplying gas to the header.
- 20 5. In a furnace fuel feeding apparatus, a header having branches, fuel feeding pipes connected thereto, burners radiating from the said pipes diagonally with relation to the axes thereof, said burners each comprising a tube carried by a pipe and having means for regulating the flow of fuel through said tube and a head having vents therein applied to the tube, a hollow body forming an extension of the head and having a flanged extension forming a baffle partly guarding the outer end of the body, a steam pipe extending into the header and having jets discharging into the said fuel feeding pipes.
- 25 6. In a furnace fuel feeding apparatus, a header having branches, fuel feeding pipes connected thereto, burners radiating from the said pipes diagonally with relation to the axes thereof, said burners each comprising a tube carried by a pipe and having means for regulating the flow of fuel through said tube and a head having vents therein applied to the tube, a hollow body forming an extension of the head and having a flanged extension forming a baffle partly guarding the outer end of the body, means for supplying gas and steam to the header and pipe therein, and means for simultaneously controlling the passage of gas and steam thereto.

WILLIAM E. HANCOCK.
